UNITED STATES PATENT OFFICE.

JOSEPH E. HOLVECK, OF PITTSBURGH, PENNSYLVANIA.

PUMP.

Application filed June 28, 1926. Serial No. 118,807.

This invention relates to pumps and more particularly to that type adapted to provide a variable delivery in accordance with variations in demand, but without any variation in the speed at which the pump is driven.

An object of this invention is to provide a pump unit of the type set forth of improved construction and having a simplified method of control.

A further object is to provide a constant speed, variable delivery pump which is simple and rugged in construction, reliable in operation and relatively cheap to manufacture and assemble.

These and other objects which will be apparent to those skilled in this particular art are accomplished by means of the present invention which is illustrated in the accompanying drawings, wherein Figure 1 is a view in elevation of a pump unit constructed in accordance with one form of this invention. Fig. 2 is a transverse sectional view on the line 2-2 of Fig. 1. Fig. 3 is a similar view on the line 3-3 of Fig. 1. Fig. 4 is a sectional view on the line 4-4 of Fig. 3. Figs. 5 and 6 are diagrammatic views illustrating certain details of operation herein-after described, and Fig. 7 is a view similar to Fig. 2 showing the application of the invention to a different form of pump unit.

The particular embodiment of the present invention which has been chosen for the purposes of illustration may be applied to a pump unit having any desired number of cylinders and includes separate crank shafts, the axial positions of which are fixed relatively to each other. The crank shafts are connected by suitable connecting rods with the plunger mechanism of the pump cylinders in such a way that a variation in the relative timing of the crank shafts results in a variation in the delivery of the associated pump unit.

As illustrated, the invention is applied to a triple cylinder pump 10 having the usual pressure chambers 11 provided with associated plungers 12, only one of which is shown in the drawing for the sake of simplicity.

Each plunger chamber has the usual spring pressed inlet or suction valve 13 provided with a valve stem or rod 14 and a discharge valve 15 leading to a discharge outlet 16.

The operating mechanism for each plunger is such that the stroke of the plunger can be varied so as to vary the delivery from the

different pump chambers. As illustrated in Figs. 1 and 2, this mechanism includes a cross head 17 pivoted by a pin 18 to the upper end of each plunger. One end of each cross head is connected to an associated crank shaft 19 by suitable connecting rods 20 and the other end of each cross head is connected to a crank shaft 21 by similar rods 22. Each crank shaft is rotatably mounted in stationary bearings so that the axes of the shafts are fixed relatively to each other. The vertical movements of the pump plungers are guided by a cradle 23 mounted between uprights 24 upon which the crank shaft bearings may conveniently be mounted.

Any convenient source of power such, for example, as a motor 25 can be used to drive the pump. As illustrated, the motor armature is connected to a drive shaft 26 having a gear 27 meshing with a driving gear 28 on the crank shaft 21. The two crank shafts are geared together for unitary movement and the gearing connecting them is of such construction that the relative timing of the two shafts may be varied so as to vary the stroke of the associated plungers. As illustrated, this gearing includes a spur gear 29 secured to the crank shaft 21 and meshing with the external teeth of an annular gear 30 rotatably mounted upon the associated crank shaft 19. An arm 31 is rotatably mounted upon the crank shaft 19 and at one end is provided with a stub shaft 32 pinned to the arm and projecting into the hollow annular gear 30. A spur gear 33 is rotatably mounted upon the projecting end of the stub shaft and meshes with the internal teeth of the annular gear 30 on one side and a spur gear 34 keyed to the shaft 19 within the annular gear 30 on the other side. The opposite end of the arm 31 has a stub shaft 35 rotatably mounted therein and extending into the annular gear on the opposite side of the crank shaft from the planetary gear 33. A second planetary gear 36 is keyed to the stub shaft 35 and meshes with the internal teeth of the annular gear 30 on one side and with the spur gear keyed to the crank shaft on the other side. A crank arm 37 is secured to the opposite end of the stub shaft 35 and connected to a rod 38 for a purpose to be hereinafter described. The planetary gear supporting arm 31 has a flange or extension 39 connected by a connecting rod 40 with a plunger 41 received within a cylinder 42, the lower end of which is connected by a

100
105
110

pipe 43 with the discharge manifold of the pump so that the piston 41 is affected by any variation in the pressure of the pump discharge. A coil spring 44 is provided between a cross head 45 secured to the plunger 41 and a stationary cross head 46 mounted upon rods 47 extending upwardly from supports 48 secured to the cylinder 42, see Fig. 3. Obviously, an increase in the discharge pressure will elevate the planetary gear shifting piston 41 against the pressure of the spring 44 so as to shift the planetary gear supporting arm 31, while any decrease in the discharge pressure of the pump permits the spring 44 to force the piston 41 downwardly. The lowermost limit of the connecting rod 40 and piston 41 may be set by suitable adjustment of a nut 49 threaded to the connecting rod and adapted to engage the upper stationary cross head 46.

It will be apparent that when the crank shafts are so timed that the cranks a , b and c of the shaft 21, see Fig. 6, are in time with the cooperating cranks x , y and z , respectively, of the associated shaft 19 the stroke of the pump plungers 12 will be at a maximum and the pump delivery will also be at a maximum. This occurs when the gear shifting piston 41 is in its lowest position. Any upward movement of this piston and corresponding shifting of the planetary gears 33 and 36 will vary the timing of the two crank shafts as such a movement of the planetary gears causes a shifting of the relative positions of the gears 29 and 34 keyed to the respective shafts. This in turn causes a corresponding shifting in the timing of each pair of cooperating cranks a and x etc., and a resulting decrease in the plunger travel so as to reduce the pump delivery. The gears forming the planetary gear train are so formed and of such relative sizes that the two crank shafts will revolve at the same speed when the planetary gear shifting arm 39 is stationary. The proportioning of the gears forming the gear train is such that a movement of 45° of the gear supporting arm 39 will rotate the gear 34, and consequently the crank shaft 19, 180° with respect to the associated crank shaft 21. If the respective crank shafts are in the position diagrammatically illustrated in Fig. 6, wherein each two associated cranks connected to the same piston rise and fall together, the delivery of the pump unit will be at a maximum, as above pointed out. If, now, the demand to be satisfied by the pump discharge falls the pressure built up in the discharge line will elevate the planetary gear shifting piston 41 so as to shift the planetary gears and change the relative timing of the associated crank shafts. If the demand drops sufficiently to shift the gear supporting arm 45° the crank shafts will assume the relative

positions indicated in Fig. 5, wherein each associated crank moves in opposition to the other associated crank. The result is that as one connecting rod 20 rises the other connecting rod 22 falls and there will be no appreciable movement of the associated plunger 12. Under these circumstances the pump discharge is at a minimum.

As a matter of actual practice it is impossible to obtain zero delivery by the above described mechanism, due to the angularity assumed by the connecting rods 20 and 22. In order to obtain zero delivery without stopping the pump an arrangement for unloading the pump suction valves is associated with and adapted to be operated by the mechanism for varying the timing of the crank shafts.

The connecting rod 38, heretofore referred to, is continually reciprocated by the crank arm 37 and the lower end of the connecting rod is provided with a rack 50 in mesh with and adapted to oscillate a gear 51 loosely mounted upon a hollow shaft 52. The oscillating gear has a beveled tooth 53 projecting outwardly on each side thereof, see Fig. 1. The hollow gear supporting shaft 52 is provided with diametrically opposed slots 54 and a rod 55 extends into one end of the hollow shaft and is provided with a pin 56 extending outwardly on one side of the hollow shaft through one of the slots 54 on one side of the oscillatory gear 51, and a second pin 57 extending through the other of the slots 54 on the opposite side of the oscillatory gear. The rod 55 is slideable longitudinally of the hollow shaft so that either one or the other of the projecting pins 56 and 57 can be shifted to engagement with an associated tooth 53. The outer end of the slideable rotatable rod 55 is connected to the core 58 of a solenoid 59 and is normally spring pressed outwardly by a spring 6 so as to position the pin 56 in the path of the adjacent gear tooth 53. When the solenoid is energized by closing its circuit through a switch 61 the rod 55 is shifted to the left as seen in Fig. 1 and the pin 57 is moved into engagement with the associated gear tooth 53 while the pin 56 is moved out of engagement with the adjacent gear tooth. The end of the hollow shaft opposite the solenoid is connected to a rotatable shaft 62 having cams 63 secured thereto beneath each of the suction valve stems 14. It will be apparent that when the cam shaft 62 and cams 63 are in the position illustrated in Fig. 2 the pump will be loaded, but that a movement of 180° of the cam shaft will cause the suction valve stems 14 to be elevated by the high parts of the associated cams so that the suction valves will be held away from their seats and the pump cylinders unloaded. The unloading cams are so positioned upon the support- 130

ing shaft 62 that the pump will be unloaded and the delivery reduced to zero when the solenoid 59 is de-energized. This permits the spring 60 to expand and move the rod pin 56 into the path of the oscillating gear tooth 53 as shown. The oscillating gear 51 and gear tooth 53 oscillate through an arc of 180° so that the 180° movement of the hollow shaft 52 and cams 63 causes the suction valves of the pump to be unloaded. By energizing the solenoid the pin 56 is moved away from the oscillatory gear and the pin 57 is moved into the path of the adjacent gear tooth 53 upon its side of the oscillatory gear. It is apparent that this causes the cam shaft 62 and cams 63 to be rotated another 180° , resulting in the low parts of the cams being positioned opposite the suction valves so that the latter are permitted to close and the pump is loaded. The beveling of the teeth 53, see Fig. 1, prevents the pins 56 and 57 from being moved except in the desired direction. Backward rotation of the unloading cams is impossible.

Advantage is taken of this form of operation for automatically unloading the pump when the demand drops to zero and automatically loading again when there is a further demand. As illustrated, this automatic control consists of a switch 64 positioned in the solenoid circuit, see Fig. 1, and adapted to be normally closed. The switch is provided with an operating handle or projection 65 which extends into the path of movement of the slideable cross head 45 movable with the planetary gear operating piston. As heretofore pointed out, when the demand for the pump discharge drops the discharge pressure will be increased so that the planetary gear shifting plunger 41 and cross head 45 are moved upwardly against the pressure of the spring 44. As also pointed out, this upward movement causes such a rotation of the planetary gearing as to change the timing of the respective crank shafts in such a manner as to reduce the amount of fluid delivered by the pump. Even when the crank shafts are timed 180° apart, however, it is impossible to obtain absolute zero delivery by such a construction, due to the relative angularity of the various connecting rods. That is to say, that even with the cranks α and α positioned as shown in Fig. 5 there would be some movement given to the plunger 12. The automatic switch 64, however, provides a simple means of obtaining zero delivery. If there is no demand whatever for pump delivery the cross head 45 will continue to move upwardly as long as there is any discharge from the pump and this upward movement will finally cause the cross head to engage the switch 64 and break the solenoid circuit, permitting the spring 60 to expand

and resulting in such a movement of the unloading cam 63 as will unload the pump. When the demand is again in evidence the downward movement of the cross head 45 will cause the switch 64 to close the solenoid circuit and again load the pump. The manually operable switch 61 is, of course, normally closed during operation of the pump.

It will be apparent that the crank arm 37 rotates simultaneously with, and at the same speed as the pump crank shafts. The cams 63 are rotated by an upward movement of the crank arm 37 and the latter is so timed that each cylinder will load only at the beginning of a discharge stroke. This is to say, the cams 63 will be rotated only during the suction strokes of the various cylinders. This prevents the pump loading with a sudden jar and causes a gradual increase in torque from zero to maximum instead of a sudden jarring increase to maximum torque resulting in excessive strains and wear.

The invention is shown applied to a somewhat different form of a pump unit in Fig. 7. In this case each crank shaft 70 is connected by a connecting rod 71 with separate plungers 72 which operate in the pressure chamber 11. The operation and effect is the same as in the more fully described embodiment. The two corresponding shafts are connected by the same form of automatically variable planetary gearing and it will be apparent that a variation of the timing of the two crank shafts will vary the timing of the strokes of the separate plungers 72 in such a way as to cause a corresponding variation in the pump delivery.

Although I have described a specific embodiment of this invention it will be apparent that various changes, additions, modifications and substitutions can be made therein without departing from the spirit of the invention or the scope of the appended claims.

What I claim as new and desire to secure by Letters Patent is:

1. A variable delivery pump having in combination parallel operating shafts rotatably mounted in fixed relation and means for varying the relative timing of said shafts.

2. A variable delivery pump having in combination parallel crank shafts mounted in fixed relation to each other and means for changing the relative timing of said shafts for varying the delivery of said pump.

3. The combination in a pump of two parallel fixed crank shafts and means for varying the timing of said shafts during operation of the pump so as to vary the delivery of said pump without changing the speed thereof.

4. The combination in a variable delivery pump of two parallel crank shafts mounted in fixed relation, gears connecting said crank shafts for simultaneous operation, means for driving said crank shafts and means for varying the relation of said gears so as to change the timing of said crank shafts and vary the delivery of said pump.
5. The combination in a variable delivery pump of two parallel crank shafts mounted in fixed relation, a planetary gear train connecting said shafts for simultaneous rotation, means for driving said shafts and means for so controlling said planetary gear train as to vary the timing of said crank shafts so as to vary the delivery of said pump.
6. The combination in a variable delivery pump of parallel crank shafts mounted in fixed relation, a planetary gear train connecting said crank shafts for simultaneous rotation, means for driving said shafts and means subject to the discharge pressure of the pump for so controlling said gear train as to vary the timing of said crank shafts and vary the delivery of said pump in accordance with changes in the discharge pressure thereof.
7. The combination in a variable delivery pump of a pair of crank shafts adapted to be simultaneously rotated, plunger mechanism operated by said crank shafts, means for simultaneously rotating said crank shafts including an annular gear connected to one of said shafts by intermediate planetary gears and means for shifting said planetary gears relatively to said annular gear so as to vary the relative timing of said crank shaft.
8. The combination in a variable delivery pump of crank shafts mounted in fixed relation, a gear on each of said shafts for simultaneously rotating said shafts, an annular gear supported upon one of said shafts and meshing with the gear on the other of said shafts, planetary gearing connecting said annular gear with the other of said shafts and means for shifting said gearing so as to vary the relative timing of said shafts.
9. The combination in a variable delivery pump of separate crank shafts, plunger mechanism operatively associated therewith, means for controlling the timing of said shafts so as to vary the delivery of said pump, means for loading and unloading said pump and a movable member responsive to the variations in the pressure of the pump discharge for automatically controlling the operation of said loading and unloading means.
10. The combination in a variable delivery pump of separate crank shafts, plunger mechanism operatively associated therewith, means for varying the timing of said shafts so as to vary the pump delivery, mechanism including a solenoid for loading and unloading said pump, a switch in the solenoid circuit and a movable member adapted to be shifted in accordance with variations in the pressure of the pump discharge for operating said switch so as to control said loading and unloading mechanism.
11. The combination in a variable delivery pump of separate crank shafts mounted in fixed relation, gearing connecting said crank shafts for simultaneous rotation, mechanism for loading and unloading said pump, means for operating said mechanism from said gearing, a solenoid for controlling the operation of said mechanism, a switch in the solenoid circuit and a movable member adapted to be shifted in accordance with variations in the pressure of the pump discharge for operating said switch so as to permit said pump to load and unload.
12. A variable delivery pump having in combination parallel operating shafts rotatably mounted in fixed relation and means responsive to variations in the discharge pressure of the pump for varying the relative timing of said shafts.
13. The combination in a pump of two parallel crank shafts rotatably mounted in fixed relation and means responsive to variations in the discharge pressure of the pump for varying the timing of said shafts during operation of the pump so as to vary the delivery of said pump without changing the speed thereof.
14. The combination in a variable delivery pump of two parallel crank shafts mounted in fixed relation, gears connecting said shafts for simultaneous operation, means for driving said crank shafts and means responsive to variations in the discharge pressure of the pump for varying the relation of said gears to change the timing of said crank shafts and vary the delivery of said pump.
15. The combination in a variable delivery pump of separate crank shafts, gearing connecting said shafts for simultaneous rotation, mechanism for loading and unloading said pump and means for operating said mechanism from said gearing.
16. The combination in a variable delivery pump of separate crank shafts, plunger mechanism operatively associated therewith, means for controlling the timing of said shafts so as to vary the delivery of said pump, means for loading and unloading said pump, and mechanism responsive to the variations in the pressure of the pump discharge for synchronizing the operation of said loading and unloading means with the operation of said plunger mechanism.
- In testimony whereof, I have hereunto subscribed my name this 11th day of June, 1926.

JOSEPH E. HOLVECK.
